UNITED STATES PATENT OFFICE

149,792

DESIGN FOR A WATCH AND JEWELRY DISPLAY BOX

Samuel Braun, Rockville Centre, and Max
Crystal, Forest Hills, N. Y.

Application August 15, 1946, Serial No. 132,531

Term of patent 3½ years

(Cl. D80—5)

To all whom it may concern:

Be it known that we, Samuel Braun and Max Crystal, citizens of the United States of America, residents of Rockville Centre, in the county of Nassau and State of New York, and Forest Hills, in the county of Queens and State of New York, respectively, have invented a new, original, and ornamental Design for a Watch and Jewelry Display Box, of which the following is a specification, reference being had to the accompanying drawing, forming part thereof:

Fig. 1 is a front perspective view of a watch and jewelry display box, showing our new design.

Fig. 2 is a rear perspective view thereof.

Fig. 3 is a front perspective view in open position.

We claim:

The ornamental design for a watch and jewelry display box, substantially as shown.

SAMUEL BRAUN.
MAX CRYSTAL.
